STOCKING

Max Fisher, Lower Alsace Township, Berks County, and Frederick L. Ireland, West Reading, Pa., assignors to Penn Maid Hosiery Mills, Inc., Reading, Pa., a corporation of Pennsylvania

Application December 11, 1951, Serial No. 17,686

Term of patent 14 years

(Cl. D47—7)

To all whom it may concern:

Be it known that we, Max Fisher and Frederick L. Ireland, both citizens of the United States, respectively residing at Lower Alsace township, county of Berks, State of Pennsylvania, and West Reading, county of Berks, State of Pennsylvania, have invented a new, original, and ornamental Design for Stocking, of which the following is a specification, reference being had to the accompanying drawing forming a part thereof, wherein:

We claim:

The ornamental design for a stocking, as shown.

MAX FISHER.

FREDERICK L. IRELAND.
